(57) **CLAIM**

The ornamental design for a bottle, as shown and described.

DESCRIPTION

FIG. 1 is a front elevational view of a bottle, embodying our new design;

FIG. 2 is a rear elevational view thereof;

FIG. 3 is a top planar view thereof;

FIG. 4 is a left-side elevational view thereof, the right side being a mirror image thereof; and,

FIG. 5 is a bottom planar view thereof.

The broken line showing in FIGS. 1-5 is for illustrative purposes only and forms no part of the claimed design.
